WATCHMAN'S TOUR SIGNAL SYSTEM

Henry G. Leach, Red Bank, N. J., assignor to
Electrical Industries Manufacturing Company,
New York, N. Y., a corporation of New York

Application July 26, 1930. Serial No. 471,052

1 Claim. (Cl. 177—360)

The invention relates to improvements in signalling systems, more particularly to watchman's register systems whereby signals are transmitted to a central station or other registering point only when and after the watchman has visited all of his stations in turn, and preferably in predetermined sequence. In systems of this character, it is not necessary that a record be made each time a watchman reaches a station and operates a device thereat but rather that the central station shall be notified when he begins his tour and when he completes the same. It is essential, however, that it will not be possible for the watchman to send such signal unless and after he has visited all of the different stations of the circuit.

The invention has for an object a system embodying a plurality of lock or preliminary stations adapted to be operated by a key which serves then to release a further and different key normally locked in position at a station, said released key in turn serving for unlocking a different key similarly held in the next consecutive station of a series.

A further object of the invention resides in the provision of a transmitter apparatus from which a signal is sent to suitable registering means, the same being operable only at the initiating of a round and by means of a suitable key. This key serves also to release from the first preliminary station of the round a different key for operating in succession the various lock stations as herein-after more fully set forth, and eventually freeing a further key from the final station suitable for operating a second lock element of the transmitter apparatus, the first lock element of which was locked upon completion of the starting signal previous to the removal of the corresponding key therefrom.

A still further object of the invention resides in a system which will require the watchman to retrace his route after having sent the aforesaid second signal from the transmitter apparatus and thus offering from a different direction a view of the territory covered.

Other objects of the invention reside in novel means for locking a key at its station and rendering more difficult picking of a lock; also, in the construction of the transmitter apparatus.

In carrying out the invention, the transmitter station may be located at the point where a watchman starts his round, and the same is provided with a pair of different locks. The said station is arranged through the operation of its locks to be electrically connected to a suitable registering or recording member located at some

convenient point under the supervision of the proper authority; and key-manipulated or preliminary stations are posted at various points along the route to be covered. These latter stations each comprise a pair of different locks operable by different keys, a key for the initial and a key for the final station being adapted, also, for operating the transmitter apparatus.

Normally, one key is locked at each of the preliminary stations and may not be removed therefrom until the key from the preceding station is used in the lock at said station; and the key for the initial station is obtainable only from the proper authority. This latter key is intended to be first inserted in a lock element of the transmitter and turned to operate the transmitter apparatus for giving notice at the receiving station that the watchman has reached said transmitter station; and as he is about to begin his round, the key is further operated to transmit an additional signal as well as to release the key. This particular portion of the transmitter apparatus becomes locked thereby though the key is then removable therefrom.

When this released key is then inserted in the first of the stations along the route for the purpose of turning one of the locks thereof, it becomes automatically locked therein but at the same time releases the key which, previously, had been locked at said station. This latter key, in turn, is similarly applied to the next succeeding station to release a key therefrom and so on until eventually the final station is reached and its key released.

The key released thereat is then used to transmit a signal, or preferably two signals, from the transmitter apparatus at the other of its lock elements which action, in turn, resets the first-named lock thereof and prevents also further operation of the last-actuated lock. The various operations of locking and unlocking keys at the different stations is then accomplished along the route in the reverse manner and until the key initially inserted in the first station of the route is again released. It may then be returned to the first-named lock of the transmitter apparatus for sending a signal therefrom and left therein until a round of the various stations is again to be undertaken.

The nature of the invention, however, will best be understood when described in connection with the accompanying drawings, in which:

Fig. 1 is a diagrammatic view indicating the arrangement of a plurality of stations with trans-

mitter and registering apparatus associated therewith.

Fig. 2 is a plan view of the transmitter apparatus, with portion of the cover broken away to disclose the interior.

Fig. 3 is an underneath view of the transmitter apparatus with bottom of casing removed; and Fig. 3a is a fragmentary elevation of a locking lever employed therein.

Fig. 4 is a plan view of one of the preliminary station devices.

Fig. 5 is a vertical section through one of said devices with key thereof shown locked in position.

Fig. 6 is a vertical section of a type of key which may be employed for operating said device.

Fig. 7 is a transverse vertical section through one of the station devices; and Fig. 8 is a bottom view with portion of base broken away.

Referring to Fig. 1 of the drawings, 10 designates the casing of a registering or recording apparatus of any well-known or special design and may be located at some central point or headquarters under proper supervision. This apparatus is electrically connected through the leads 11 with a transmitter station 12 located at a point where a watchman is to initiate and complete his tour of various preliminary stations 13, 14, 15, 16, 17, etc., the order of travel being as indicated by the full line arrows on the way out 30 and by the dotted line arrows on the return course.

The transmitter apparatus 12 comprises a suitable casing 20 which is sealed in the manner hereinafter set forth to prevent access to its interior; and the same is provided in its upper surface with two keyhole slots 21 and 22 respectively, these slots being adapted to receive a sleeve-protected key member of the nature more particularly shown in Fig. 6 of the drawings and adapted to fit lock barrels 21' and 22'. This key comprises the winged head 23 with shoulder portion 24 and from which extends downwardly a protective and locking sleeve 25 surrounding the key proper 26, said sleeve being provided also with the lateral projection or nose 27. By thus surrounding the actuating key portion 26 with the sleeve 25, not only is it more difficult to duplicate the said active key portion 26, but the sleeve itself is adapted for effecting locking of an inserted key, as hereinafter set forth in connection with the operation at the various stations 13, 14, etc.

The casing 20 contains, also, contact-making elements 28 which are operated by teeth 29 adapted for engagement with fingers 30 to transmit a predetermined succession of electrical impulses through the leads 11 to the registering device 10. The teeth 29 are rotated in the usual manner by a spring-motor device 31 which is manually wound by depressing a projecting finger or arm 32 accessible above the surface of casing 20—all of which is well known and forms no particular part of the present invention.

Casing 20, moreover, is divided into two compartments by a longitudinal partition 33 which substantially seals the aforementioned transmitting mechanism and barrels 21' and 22' in the primary compartment, only the terminals 34 of the transmitting apparatus being more or less accessible in the adjacent secondary compartment 35 and to which access may be had only by the breaking of a glass window 36 of the cover thereof. Access is afforded thereby to the secondary compartment through the retraction of a spring-urged locking plunger 37; and in permitting the cover to be removed also to the primary com-

partment when a further locking element, as the screw 38, is withdrawn. This screw serves to lock the cover of the primary compartment to the partition of the casing and is withdrawable only through the use of a specially-shaped tool operable in the secondary compartment. By this expedient, the transmitter apparatus is well secured against tampering; and signals therefrom may only be transmitted through operation by means of one or the other of two different keys of the nature of the key member shown in Fig. 6 and when the same is inserted in the proper socket 21 or 22.

Referring to Fig. 3 of the drawings, means are shown whereby release of the transmitter contact means is controlled in such a manner that the one key may operate, when inserted through the one key socket as the socket 21, to send successively two signals, and as well as by means of a different key inserted through the socket 22 to transmit two further signals. It is understood, however, that the second key may operate only after the other has completed its action, said second being locked in position after turning and until the sending of its first signal has been effected. This second key may be then turned back again sending an additional signal, which operation also frees the said key.

To this end, there is provided for the one lock element an oscillatable locking member 40 and for the other lock element an oscillatable locking member 41 which may be rocked in accordance with the direction the key is turned. The locking members, moreover, are each provided with an arcuate slot 42 and 43 respectively, inwardly directed from a side edge and terminating in a locking notch 44 and 45 respectively. Lateral notches 46 and 47 are also provided on the respective locking members and the same are designed to receive the inner end of a lever 48 and a lever 49 to secure a locking member after it has been turned through the required arc by a key member. These levers are urged toward the respective notches 46 and 47 by a spring 50 bearing upon the opposite end of the lever 48 and a spring 51 bearing upon the opposite end of the lever 49. When thus locked, the key may not be turned back again until the locking member is released; and, normally, one locking member is free to be turned while the other is in the locked position.

To effect the release, the arm 32 is depressed and released to thereby set in motion the signalling apparatus; and at the same time causing rotation of a cam 52 having engagement with the outer end of a lever 48 or 49 riding on the high part of said cam to disengage its inner end from a notch 46 or 47. When the key is then turned in the reverse direction the inner end of a lever moves through a slot 42 or 43 and eventually drops into its locking notch 44 or 45.

Movement of the cam, also, is terminated through engagement of pins 53 and 54 projecting at right angles from the cam engaging with the edge of a corresponding locking member 40 or 41. Thus, a key must be turned first in one direction, the signal sent, then turned in the opposite direction and a further signal sent, before the key for the other locking element may become effective to transmit signals.

The devices located at the different preliminary stations 13, 14, etc. are all alike and comprise an enclosing casing 60 having keyhole openings 61 and 62 in its top for permitting the insertion of a key sleeve 25 over suitable lock bar-

rels 63 and 64 which are mounted within the casing. The different barrels are adapted for operation by a key 26 when the head 23 of the key member is turned in the proper direction, 5 and have rigidly connected at their lower ends and below a locking plate 65 meshing gear wheels 66 and 67 to rotate therewith. As one barrel is, therefore, turned by its key, the other will be correspondingly rotated for the purpose herein- 10 after set forth.

Moreover, when a sleeve 25 of a key member is inserted into the casing through a key slot 61 or 62, its nose 27 fits a groove 68 or 69 of an upward extension 70 of the plate 65; and when 15 the key member is turned, said nose will lock thereunder to lock the casing elements together. This locking action will obtain even though the upper casing portion be unscrewed from the base 71 thereof.

20 Thus, it will not be possible to separate said casing elements to obtain access to the interior, for the said elements are securely locked, between the shoulder 24 and the nose 27, with extension 70 which is secured to said base through 25 plate 65. The base in turn is thus also not removable from a support 72 to which it has been attached, as by means of the screws 73 which are covered by a flange 74 of the casing.

It will be understood that in accordance with 30 the invention, there is always one key in position in a casing which is locked therein by its nose as hereinbefore set forth and by the usual well-known locking action of a key in its barrel.

To render more difficult picking of a lock, the 35 gear sectors 66 and 67 are provided with respective holes 75 and 76 and beneath these sectors are mounted resilient spring arms 77 and 78 having projecting pins 79 and 80 which extend upwardly therefrom and are adapted to register, in certain positions, with the respective holes or sockets 75 and 76. There extend upwardly from the spring arms further pins 81 and 82 which are coaxial with the barrels 63 and 64 and the gears 66 and 67, said pins extending 40 45 therein to a height sufficient to make contact with the corresponding key element 26 when the key is inserted.

Normally, it will be understood that there is 50 always a key inserted in the casing and the same is further locked therein against turning by a locking pin of the opposite gear sector registering with its opening upon turning the barrel with said key, which thus prevents its sector from further turning.

55 When the second key member is inserted it will depress the spring arm, through engagement of its key portion with the upstanding pin, to free the locking engagement; and, when turned as aforesaid, it will cause the previously mentioned 60 sector in mesh therewith to rotate and bring its key to a position where its nose fits into a vertical groove 68 or 69, so that when the corresponding locking pin then fits the corresponding hole of the gear wheel, said key is forced upwardly 65 under the action of the corresponding spring arm.

In turning the inserted key to effect this release, said inserted key now becomes locked in the casing and can only be removed by the insertion of a further key in the other keyhole and 70 operating the same as aforesaid. It will be understood that this feature is additional to the locking action of the key in its barrel and makes picking of the lock more difficult.

75 A complete cycle of operation is as follows: When a key is inserted, for example, in the socket

21 and given a turn, it moves locking member 41 to the right, Fig. 3, causing the outer end of lever 49 to engage in notch 47 under the influence of spring 51. This effects locking of the oscillatable locking member 41 and the inserted key. Finger 32 is then pulled downwardly to wind up the clock mechanism, whereupon it is released to send a signal. Pin 54 has been released in the meantime by the movement of member 41 to the right and is free to move in the undercut surface portion 85 41' of said member when the clock train then rotates the cam 52 one-quarter revolution and the signal wheel one-half revolution, the latter being geared accordingly. The signal wheel 29 is rotated with the cam, transmits the required signal 90 through the contact-making elements 28-29, and the key remains locked until completion of the signal when the high part of cam 52 raises the inner arm of lever 49 to disengage its outer arm from the notch 47 and thus free the key. The pin 95 53, however, has been rotated to a position engaging the circumference of member 41. To remove the key it is necessary to turn it in the reverse direction and move thereby member 41 to the left. This finally clears pin 53 permitting the 100 key to be removed and causes the cam 52 to again rotate one-quarter revolution and to send an additional signal through the contact-making elements 28 and wheel 29 which makes one-half revolution. The pin 54 stops at the edge of member 105 40 to terminate the rotation of the cam. In the turning of member 41 to the left, the outer end of lever 49 becomes locked in the notch 45 and thus prevents further turning of the key in 110 socket 21.

A watchman then starts with the released key to make his rounds; and when the round is completed after visiting the various preliminary stations and the final key has been released, it is inserted in the socket 22. The key may then be 115 turned therein and the finger 32 again pulled down to transmit the two signals with pin 54 clearing the undercut portion 40' as in the case of the insertion of a key in socket 21, the key in turning in socket 22 being locked therein through engagement of the outer end of lever arm 48 in the notch 46, completing the cycle.

I claim:

A watchman's signal system comprising a transmitter station and a series of preliminary stations to be visited by the watchman in consecutive order, a signal transmitter at the transmitter station embodying two lock members for controlling the signal operations of the transmitter, a key for one of the lock members, a different key 125 for the other lock member, means whereby one of the lock members is rendered operative to control the signal operation of the transmitter while the other is rendered inoperative to control the operation of the transmitter, means whereby the 130 signal operations of the transmitter by the operative lock operates the first means to render said operative lock member inoperative to further control the signal operation of the transmitter and to render the other lock member operative to 135 control the further operation of the transmitter and vice versa, a pair of locks at each preliminary station, a series of different keys, each lock of a pair at each station adapted to be operated by a different key while one lock of a pair at a station is adapted for operation by the same key as one of the locks of the pair at the preceding station and the other lock of the pair is adapted to be operated by the same key as one of the locks of the pair of the succeeding station, means in each 140 145 150

pair of locks whereby the operation of one of the locks by its key will retain the key against removal and will release the retained key of the other lock of the pair, one of the transmitter lock keys being designed for operation of the free lock of the first of the preliminary stations to re-

lease the retained key which key in turn operates the free lock of the next preliminary station, and so forth, the retained key of the final preliminary station constituting the other key for the other lock operating member of the transmitter.
